METHOD OF AND APPARATUS FOR PAINTING BEVELS

Samuel Krajci and Leon E. Savage, New Orleans, La., assignors to The Celotex Corporation, Chicago, Ill., a corporation of Delaware

Application April 10, 1944, Serial No. 530,340

4 Claims. (Cl. 117—43)

1

This invention is directed in part to a method of applying paint to bevels, or the like, on tile or generally similar units in production, and relates to the method of painting the bevels and to the apparatus for accomplishing such objective.

While it is a relatively simple matter to apply a coating or to paint the surface of a tile or like unit in production, it has been found to be very difficult to apply a satisfactory coating to a bevel if such is provided at the edge of the unit. The bevel being angular with respect to the surface of the unit, it follows in any ordinary application of paint thereto, that the paint tends to run down the bevel and collect along the lower edge thereof, leaving little or no paint on the upper part of the bevel, and thus a satisfactory result is very difficult to obtain.

According to the invention hereof, the method of painting the bevels is such that while the difficulty of the paint tending to run down on the bevel and to collect on the lower portion thereof is not obviated, such is offset at a stage in the processing wherein any excess of paint which has accumulated along the lower part of the bevel is redistributed over the width of the beveled surface under conditions which prevent the applied coating again running down the bevel and collecting along the lower portion thereof.

The method of painting bevels, which is disclosed in detail herein, involves conveying the units along a horizontal path, and wherein, as the unit progresses along its path, the beveled portions thereof are subjected first to a hot burnishing, followed by the application of paint to the bevel, the removal of excess paint, a partial drying of the applied paint, redistribution of and final drying of the applied paint coating on the bevels, and finally an ironing operation which smooths out any slight overlap of the applied paint coating on the horizontal surface.

The apparatus for carrying out the foregoing described method for the painting of bevels comprises suitable framework supporting a conveyor for conveying the units through a horizontal path, and also supporting along such path the various apparatus which are required for carrying out the method of painting, and which comprise the burnishing devices, the paint supply system, including paint discharge nozzles, air jet nozzles, a drier section, beveled heated rolls for the redistribution of and drying of the applied paint, and finally the surface roll. It is to be understood that with the apparatus as illustrated and described, the two opposite edge bevels of a unit are painted, and that for the painting of the

2

other two opposite edges the unit, after being turned 90°, is either again run through the apparatus or there is provided a similar apparatus which may be arranged so as to receive the units from the first apparatus and take them off at right angles, or the second apparatus may be arranged directly beyond the first apparatus with intervening mechanism for turning the units 90° as they pass from the first to the second apparatus.

The invention hereof will be described in detail in connection with the accompanying drawings, wherein:

15 Figure 1 is a plan view of the apparatus;

Figure 2 is a side elevation of the apparatus;

Figure 3 is a section of the apparatus taken on line 3—3 of Figure 1 showing the painting system;

20 Figure 4 is an enlarged detail of the painting nozzle;

Figure 5 is a plan view further illustrating details of the paint nozzle mounting of Figure 3;

Figure 6 is a section taken on line 6—6 of Figure 1;

25 Figure 7 is a sectional view on line 7—7 of Figure 6;

Figure 8 is enlarged side elevation of the burnishing iron shown in Figures 6 and 7;

Figure 9 is an end view of the burnishing iron shown in Figure 8;

Figure 10 is a plan view taken over one of the air jet nozzles;

Figure 11 is an elevation of the structure shown in Figure 10;

35 Figure 12 is a detail illustrating an air nozzle;

Figure 13 is a section taken on line 13—13 of Figure 1;

Figure 14 is a side elevation of the structure shown in Figure 13; and

40 Figure 15 is a sectional view taken on line 15—15 of Figure 13.

In the drawings, the apparatus is shown as comprising suitable framework, such as legs 20 on which are mounted longitudinal members such as 21 and 22 to constitute a generally table-like structure or framework. On the framework of the apparatus there is mounted a conveyor mechanism comprising the conveyor belt 23, which is trained over suitable idler rollers 24 and live roll 25, a driven roll which drives the conveyor 23 and in turn is driven from a prime mover by a suitable drive shown as belt 26 driven from prime mover units comprising an electric motor 27 and speed reducer 28. As will be readily understood, when the prime mover unit operates to

drive belt 26, this in turn drives live conveyor roll 25 to actuate the conveyor belts 23 which are trained over this live conveyor roll 25. The conveyor belt 23 preferably has thereon suitably spaced cleats or dogs 29, of which, for simplicity, only several are shown in the drawing at the right end portion of Figure 2. The cleats or dogs are suitably spaced to receive the tiles or units which are to be operated upon, and they not only serve to position the units on the conveyor belt, but they also serve to slightly space the units one from another as they are conveyed through the process of painting the bevels thereof.

Tiles or units, the bevels of which are to be painted, may be units of material cut to the proper size and provided with bevels or preferably, the units, the bevels of which are to be painted, will have already had a surface coat applied thereto, and which may have been applied to the material while in large sheets. When surface coated large sheets are cut up into tile form and the cut pieces are beveled around their top edges, these bevels, of course, are raw; that is, they are cut surfaces resulting from the forming of the bevels, and it is these unpainted bevels which the apparatus hereof is particularly fitted to apply to such bevels a paint coating.

Suitably cut and beveled tiles or units are supplied to the apparatus at the right-hand end, as seen in Figure 2, where they may be fed to the machine from feed table 30, or a stack of these units may be placed in the feed hopper 31 from which they are picked up, one by one, by the dogs 29 on the conveyor 23.

As a tile unit is picked up by the conveyor and starts on its travel through the apparatus, there is first encountered an edge burnishing iron which is located at station 32 where the heated burnishing iron, which is disclosed in detail in Figures 6 to 9, burnishes the beveled edges so as to provide a smoother surface for the application of the paint coating. The burnishing iron and its mounting, shown in detail in Figures 6 to 9, comprise an iron body 33 having an ironing face or portion 34 which, as shown, is preferably somewhat curved on its forward end, as at 35, so that the tile or unit, the bevel of which is to be ironed, may readily pass under the ironing face. While the exact shape of the burnishing iron body 33 is relatively immaterial, it is illustrated as a generally annular member, which adjacent each end has formed thereon a square portion 36 providing for the mounting of the iron body 33 in a guide-way 37 so that the iron body may move with a limited vertical movement, will be prevented from turning in its mounting, and the ironing face 34 may be pressed into contact with the surface of the bevel which is to be ironed or burnished. The square portions 36 on the iron bodies 33 are mounted in guide-ways 37, and the square portion 36, in cooperation with the faces of the guide-way 37, provide for a limited vertical movement of the iron body 33, and it is evident that the iron body will be prevented from turning. By the provision of springs 38 positioned between the yoke portion of the guide-way 37 and the upper face of the square portion 36 on the iron body 33, the burnishing iron face 34 is consequently at all times spring-pressed against the surface to be burnished. The annular iron body 33 is adapted to receive within its central opening a suitable heating means which, most conveniently, is an electrical heater which may be slid into the annular opening and may be connected by wires 39 to a suitable source of elec-

trical energy, and in connection with which it will, of course, be understood that suitable variable resistance or the like will be included in the circuit so that the temperature of the burnishing iron face 34 can be controlled and maintained at the desired temperature.

The burnishing irons 33 are mounted, one on each side of the apparatus, so that two edges of a tile or unit may be burnished as the tile passes the burnishing iron station 32, and the burnishing irons are shown as mounted on cross members 40 which extend across the width of the apparatus and are mounted at their ends on lugs 41, which are welded or otherwise suitably connected to the framework of the apparatus, and in connection with which wing nuts 42 are provided for securing the mounting member 40 securely in place.

For burnishing the beveled edges of tiles or units fabricated from fiber insulation board, and particularly from bagasse fiber board, the temperature is preferably maintained at around 500° F. which, it has been found, is a suitable temperature for accomplishing the desired burnishing action, particularly when the tiles are being conveyed on the conveyor 23 at a lineal speed of about 52 ft. per minute, which is roughly 1 ft. per second, with the result that a tile 1 ft. long will pass under the burnishing iron in approximately 1 second. Actually, on an apparatus such as is disclosed operating at 52 ft. per minute, the number of tiles handled per minute, due to the fact that they are spaced somewhat on the conveyor, is 42 tiles per minute, which would mean that a tile would be under the burnishing iron for approximately three-fourths of a second, but this allows sufficient time for a good, smooth burnishing of the beveled surface.

From the burnishing iron station 32, the tile 40 is then conveyed to the paint application station 45, at which point paint spray nozzles, shown in more detail in Figures 3 and 4, discharge paint onto the bevels to be coated. The edge painting system, which is positioned at station 45, comprises a paint tank and a pump which pumps the paint from the tank to the paint nozzles which discharge the paint onto the edge bevels, with the excess running down over the edges of the tile and being caught in the upper part of the paint tank, which is a flared hopper, then flowing through a screen and returning to the body of paint in the paint tank. The paint tank, which is shown at 46, is merely a receptacle for the paint, but which is preferably provided with a paint stirrer 47 so as to keep the paint in the tank thoroughly mixed. Paint is drawn off from the bottom of tank 46 by pipe 48 which discharges to pump 49 driven by prime mover 50, which is indicated as an electric motor. Pump 49 pumps the paint up through pipe 51 to supply paint sprays or nozzles 52. The paint nozzles 52 are suitably mounted on cross members which are similar to the cross members 40 particularly described in connection with the mounting of the burnishing irons, and has a mounting thereon for the purpose of adjustment, which is clearly obvious from the drawing without detailed description thereof, and since various equivalent modifications of the mounting might be adopted, such will not be described in detail. It is merely to be noted that the paint nozzles 52 are preferably so mounted on cross member 40 that they may be adjusted universally with respect to the bevel to be painted and, as illustrated, this is accomplished by the provision of clamping mountings

53 and 54 arranged one at right angles to the other. The paint nozzles 52 are illustrated as discharging approximately parallel to the surface to be coated, and so arranged that a slight amount of paint will be deposited along the edge of the top surface of the tile adjacent the beveled surfaces. Of course, with any particular type of nozzle the best angle of the nozzle, with respect to the beveled surface, for obtaining a good coating can only be determined by adjustment as the apparatus is being operated, and it is contemplated that the exact adjustment of the nozzles will be made when the apparatus is in operation. The paint stirrer 41 in the paint tank is mounted on a shaft 55 which is carried through the sides of the tank in stuffing boxes 56, and the stirrer is suitably revolved as by a pulley 57 mounted on shaft 55 and driven by belt 58.

After the bevels of the tile unit are painted at station 45, the conveyor 23 carries the tile to station 60 where there are provided air jets for blowing excess paint from the edge bevel and adjacent thereto. The air jets for blowing the excess paint from the edges of the tiles are preferably ribbon-like jets; that is, wide, thin jets of air such as would be discharged from the orifice 61 provided in air jet head 62. The air jet heads are mounted, as shown in detail in Figures 10 and 11 of the drawing, on cross members 63 which are suitably mounted on elements of the framework of the apparatus, and are mounted thereon with clamping connections 64 and 65 arranged at right angles, one to the other, so that the nozzles are mounted on a universal mounting with respect to the tile bevel. The air jet heads 62 are preferably positioned so that the air jet issuing from nozzle 61 is directed substantially parallel to the painted bevel, but preferably a portion of the jet strikes the surface of the tile just behind the beveled edge so that any excess paint which has flowed onto the tile surface will be blown off, as well as any excess paint on the painted bevel. The air jet head 62 is suitably connected to an air supply 66 through which air under pressure is supplied to provide the desired air blast at the air jet orifice 61.

It will be noted, as is particularly shown in Figures 3 and 6 of the drawings, that the framework of the apparatus includes cross members 70 on which are mounted horizontally extending slideways 71 on which tile units being processed are carried along by the conveyor belt 23 being pushed or propelled by the cleats or dogs 29 secured thereon. These slideways 71 may be of any suitable material, such as hardwood or smooth finished metal, or the like, as their function is merely that of supporting the tiles being carried through the apparatus and to provide a surface along which the tiles slide as they are propelled through the apparatus.

After the excess paint has been blown from the edges of the tile by the air blast at station 60, they are carried by the conveyor to an elongated drying section where the edges of the tile pass under the horizontally extending pipes 73 which are positioned over the beveled edges of the tile as they are carried along by conveyor 23. These drier pipes 73 are merely lengths of pipe, conveniently $\frac{3}{4}$ inch pipe, drilled on their under side with small holes about $\frac{3}{8}$ inch in diameter spaced 1 inch apart. These drier pipes 73 are supplied with heated air from an air heating furnace 74 in which is positioned an air heating coil 75 which supplies the drier pipes 73. The air heating furnace 74, shown in the drawing, is merely a

diagrammatic source of heat for heating the drying air, and it may actually constitute any suitable means for heating the air supply to pipe 71, and the required heat for heating the air 5 may be supplied either by gas jets, by electrical heaters, by steam, or other heating unit. Air under a slight positive pressure is fed to the air 10 heating coil 75, and from there the heated air passes out through the drier pipes 73 issuing 15 on the under side from the small drilled holes referred to, to provide heated air currents blowing down over the path of the painted bevels of the tiles as they are propelled along the section of the apparatus over which the drier pipes 73 are positioned.

Beyond the paint drying section of the apparatus there is provided a beveled edge hot iron which serves the dual purpose, to some extent, of redistributing the paint coating which has 20 been applied to the coating, as well as to iron and smooth the paint coating, and, in addition, this beveled hot ironing apparatus serves to completely dry the paint coating which preferably is not dried completely bone-dry under the 25 drying pipes 73 of the drying portion of the apparatus.

The bevel hot ironing section or station of the apparatus is indicated generally at 80. The detail 30 of the bevel hot ironing portion of the apparatus is shown in Figures 13 to 15 and wherein there is shown an insulated housing 81 in which this portion of the apparatus is housed. The bevel hot ironing apparatus comprises the housing 81 referred to, suitably positioned over the conveyor 35 portion of the apparatus and having mounted therein the heated bevel irons. Heated bevel irons 82 are narrow cylinders with bevel faces corresponding to the bevels to be ironed, and which are mounted on a driving shaft 83 mounted 40 in journals in turn mounted in vertical journal guide-ways 84 for vertical movement, and provided with springs 85 to press downwardly on the shaft 83 to provide the desired pressure of the bevel hot irons on the painted bevels against 45 which they are operating. The shaft 83 is suitably rotated by means of a belt 86 which drives the pulley 87 mounted on the shaft 83.

For heating the bevel hot irons 82 there may 50 be provided gas burners, which are shown at 88, and which are supplied from gas pipes 89. The gas flames issuing from the gas burner 88 impinge upon the bevel hot irons 82 to preferably maintain the beveled surfaces thereof at about 600° F.

55 The bevel hot irons 82 are preferably of relatively large diameter, that is in the neighborhood of 18 inches, and as such should be driven at a speed which is substantially that of the linear rate of travel of the units thereof, the bevels of which are to be hot ironed. As the units, the bevels of 60 which have been coated with paint at a preceding station in the apparatus with the paint coating substantially dried in the drying portion, are carried along by the conveyor under the hot roll irons 82, these irons revolving against the coated and substantially dried bevels serve somewhat to redistribute the paint coating thereon uniformly should it not be uniform; the action 65 smooths the surface of this paint coating and the heat of ironing completes the drying of the coating.

70 The conveyor now carries the almost finished units under surface rolls which are relatively narrow rolls that operate against the surface of the tiles adjacent the edge bevels. In painting the 75 tile bevels it is preferred that the paint coating

applied lap slightly onto the top surface of the tile; but since this overlap is quite likely to show unless it is given some treatment, there are provided narrow surface rolls which have been referred to, and which serve to smooth down and even out this slight overlap of the paint coating on the surface of the tiles adjacent the bevels so this overlap is not noticeable. The surface rolls referred to are shown at 90 and are merely narrow cylinders, preferably about 2 inches wide, so positioned as to operate against the top surface of the tile adjacent the bevels. These surface rolls 90 which, if desired, may be somewhat heated by gas jets played thereon, are mounted on a shaft 91 driven by belt 92 which drives a pulley 93 mounted on the shaft 91. Shaft 91 will, of course, be understood to be suitably mounted in bearings preferably mounted in journal guides, similar to journal guides 84 and spring-pressed as by springs 85, the journal guides, of course, being suitably mounted on the framework of the apparatus. As the tiles are carried along under these driven surface rolls 90 they serve to smooth out and uniformly distribute the small bead of paint which may be on the surface of the tiles adjacent the bevel, and thus this paint overlap is made inconspicuous.

After the tiles pass the surface rolls 90 they may be then taken from the conveyor at the far end of the apparatus.

The paint which is preferred for painting the bevels, particularly of fiber board tile, is a so-called casein water paint which, basically, consists of casein dissolved with lime as the adhesive, and carrying suitable filler and pigment to provide a coating of the color desired. For a white paint coating, ordinarily the white color is obtained by the use of lithopone pigment and a white clay as a filler. These casein water paints, either in powder or paste form, are generally available on the market, and those skilled in the art involved know the composition of these paints and understand their application. Therefore, it is felt that a detailed explanation with respect thereto is entirely unnecessary and consequently such is not given.

Briefly summarizing the operation of providing painted bevels on tile units and the like, and particularly on tile units fabricated from pre-painted fiber insulation board, the sequence of operation is as follows:

The fabricated tile units having edge bevels, are propelled through a horizontal path on suitable support means by means of a conveyor. The conveyed tiles pass under hot burnishing irons which smooth down and burnish the bevels; then the tiles pass under paint applying nozzles which apply paint to the bevels, the excess running down over the edge of the tiles and being returned to the paint tank from which it is recirculated. After the paint coating has been applied to the bevels, the tiles pass under air jets which blow any excess paint from the bevels, and they then pass to a drier section where heated air blowing against the painted bevels substantially dries the paint. From the drying section the tile, with the bevels covered with paint and substantially dry, passes under the bevel hot rolls where the heated hot rolls smooth out and complete the drying of the paint coat on the bevels, and from this stage the tiles pass on to be carried under face edge rolls which roll down and smooth out any paint which has overlapped from the bevel onto the upper face of the tile.

From the foregoing it will be seen that there has

been provided an apparatus with a plurality of stages for carrying out the different operations which are required for obtaining a good paint coating upon a bevelled surface of a tile-like member, particularly one the base of which is fiber insulation board. The various operations of hot burnishing the surface to be painted, applying a surplus of paint, removal of the excess applied paint by an air jet, the partial drying, and finally the bevel hot rolling to uniformly distribute the paint coating on the bevel and fully drying it, with the subsequent step of smoothing out any overlap on the face of the tile, constitutes a series of operations which very satisfactorily accomplishes the desired result of obtaining a smooth and satisfactory paint coating on the bevelled edge.

In the foregoing there is described in detail the method for applying a smooth finishing coat, particularly to a bevel or like inclined surface, and there has been, in addition, described in detail the apparatus for carrying out the method in obtaining the smooth and uniform finish. In connection with the various elements of the apparatus, it is to be understood, of course, that those skilled in the art may substitute equivalent elements as, for example, instead of drying the painted bevels in a current of hot air, they might alternatively be dried by providing a battery of 30 radiant drying lamps, etc., and it is intended that obvious alternatives or adaptions may be utilized, if desired.

What we claim is:

1. An apparatus for applying a finished paint coating to a bevel face comprising in combination a heated bevel burnishing iron, a paint applying means, means for removing excess applied paint, means for drying the applied paint coating, a pressure applying bevel hot roll and a conveyor 35 conveying an article, having a bevel edge, successively past the aforesaid elements of the apparatus with the bevel edge in operative relation thereto.
2. An apparatus providing a finishing surface coating comprising a plurality of operative means 45 in combination with a conveyor for conveying the material in operative relation thereto and wherein the operative means comprise, a heated burnishing iron, a paint applying nozzle, an air blast nozzle, a drying apparatus, and a driven coating redistributing, smoothing and drying device.
3. An apparatus for applying a finishing paint coating to a bevel face comprising in combination a conveyor for conveying the material to be coated 50 in a substantially horizontal plane, a nozzle associated in operative relation with said conveyor substantially over the inner edge of a bevel to be coated, and discharging the coating material across said bevel surface, a coating circulating system comprising a pump and conduit, the nozzle comprising a portion of the circulating system, said circulating system receiving and recirculating excess coating material flowing off the bevel, an air blast nozzle positioned adjacent the bevel 55 and discharging an air blast substantially normal to the coated bevelled surface, means drying the applied coating, and finally a heated burnishing iron having a heated face which is normal to the coated bevel, the said elements of the combination being arranged in successive order as set out; with relation thereof to the conveyor, such that the material advanced by the conveyor is successively acted upon by the said various means for applying the coating material, for removing the excess thereof and for partially drying the coat.

ing, and finally redistributing, completing the drying of and burnishing the applied coating.

4. The method of providing a smooth finishing coating on an inclined edge surface of a beveled fiberboard tile and comprising the steps: smoothing and burnishing the beveled surface with a heated iron, flooding the beveled surface by flowing a stream of a film-forming paint coating downwardly across such surface to be coated, immediately subsequently to the application of the 10 stream of paint coating, removing excess coating by means of an air jet directed substantially parallel to and across the inclined surface, then partially setting the applied material, and by hot ironing to redistribute, smooth and completely set 15 the applied coating.

SAMUEL KRAJCI.
